MILK TANK

William E. Rich, 1720 S. Yale, Wichita, Kans.

Filed Apr. 21, 1958, Ser. No. 50,547

Term of patent 7 years

(Cl. D23—1)

FIG. 1

FIG. 3

FIG. 2

Fig. 1 is a perspective view of a milk tank showing my new design.

Fig. 2 is a left side elevational view of same.

Fig. 3 is a left end elevational view of same.

The appearance of the undisclosed side is the same as the side shown.

I claim:

The ornamental design for a milk tank, as shown and described.
